UNITED STATES PATENT OFFICE.

ARTHUR J. HALL, OF PITTSBURGH, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed March 7, 1919. Serial No. 281,187.

To all whom it may concern:

Be it known that I, ARTHUR J. HALL, a subject of the King of Great Britain, and a resident of Pittsburgh, in the county of 5 Allegheny and State of Pennsylvania, have invented a new and useful Improvement in Control Apparatus, of which the following is a specification.

My invention relates to control apparatus and particularly to unit switches for use in electric railway systems and the like.

One object of my invention is to provide a simple and reliable device of the above-indicated character which shall effectively 15 dissipate the arcs that are formed between the separating contact members, with a minimum degree of deterioration of the apparatus.

More specifically stated, the object of my 20 invention is to provide a unit switch comprising a stationary and a movable contact member, two blowout coils alined with the contact members and located on opposite sides thereof, together with a barrier 25 of insulating material disposed opposite the contact members to split or divide the above-mentioned arcs, which thereupon are carried along removable conducting shields for the blowout coils and are effectively 30 dissipated.

My invention may best be understood by reference to the accompanying drawing, wherein—

Figure 1 is a view, in side elevation, with 35 parts removed, of a switch constructed in accordance with my present invention.

Fig. 2 is a sectional view taken along the line II—II of Fig. 1.

Referring to the drawing, the apparatus 40 here shown comprises a stationary contact member 1; a co-operating movable contact member 2; a pair of magnetic blowout coils 3 and 4 which are located in alinement with the contact members on opposite sides thereof; a pair of detachable curved coil shields 5 and 6 for the blowout coils 3 and 4, respectively; a plurality of terminal members 7 and 8 for the switch; a suitable arc chute or box 9 and a barrier 10 of insulating material that is located substantially 45 opposite the contact members 1 and 2.

The stationary contact member 1 is provided with an arcing tip or horn 15 of a familiar type, the two members being electrically secured to a conducting block or 50

terminal 17 which, in turn, is mounted upon a slab or bar 18 of insulating material by means of a suitable bolt and nut 19. One end 20 of the strap conductor comprising the blowout coil 3 is also secured 60 to the bolt 19, the other end of the coil being likewise attached to a bolt 21 that extends through the insulating slab 18 and to the outer end of which is secured the terminal member 7 for receiving a wire or 65 conductor from the external circuit.

The movable contact member 2 is also provided with an arcing tip or horn 16 and is associated with the blowout coil 4 and the exterior terminal member 8 in a 70 manner similar to that just described. In addition, a suitable flexible shunt member 25 is secured to the parts of the movable contact device in a familiar manner, and an operating rod or stem 26 is provided for the purpose of effecting contact 75 of the movable member 2 with the stationary member 1. Since the particular structure that is employed for this purpose is not material to my present invention, and since the general type of movable contact device that is illustrated is familiar in the art, I do not deem it necessary to provide further description.

The blowout coil 3 comprises a plurality 80 of convolutions 28 of strap copper, or the like, that are wound around a magnetizable core member 29. A plurality of reinforcing plates 30 of asbestos-board, or other similar insulating material, are located on the respective sides of the blowout coil, the entire combination of apparatus being assembled by means of a plurality of screws 31 and 32 that extend into a tapped opening of the core member 29.

The blowout coil 4 is similarly constructed and arranged, and no further description is believed to be required.

Each of the conducting coil shields 5 and 6 comprises a flat metallic strip that follows the general contour of the associated blowout coil for approximately three-fourths of the coil's circumference and has one end suitably secured to the conducting block 17 by means of a small screw 35, 100 while the other end is flanged and secured by a screw 37 to another block or stud 36 on the opposite side of the blowout coil, which stud is suitably attached to the insulating slab 18.

The conducting guide members 5 and 6 are thus simple and inexpensive in construction and may be readily replaced when burned or pitted by the arcs that are formed 5 between the separating contact members 1 and 2.

The arc chute or box 9 is of a familiar general type, being composed of asbestos lumber, or the like, for the purpose of 10 suitably enclosing the unit-switch apparatus and guiding the dissipating arcs in the proper direction.

The barrier 10 may be composed of soapstone or similar material and has a beveled 15 edge located in proximity to the contact members 1 and 2. The barrier may readily be secured to the arc chute 9 by means of screws or the like.

The operation of the illustrated apparatus 20 may be briefly set forth as follows. Assuming that the movable contact member 2 has been actuated to its closed position, namely, in contact with the stationary member 1, to conduct current from the terminal 25 7, for example, through the blowout coil 3, the contact members 1 and 2 and the blowout coil 4 to the other terminal 8, then, upon separation of the contact members during the opening of the switch, an arc 30 is produced and, in the present instance, this arc, which is inductively quenched in a well-known manner by means of the two blowout coils 3 and 4, is split or divided by the insulating barrier 10, the parts or 35 divisions of the arc then respectively following, or being guided along, the conducting paths provided by the arcing tip 15 in conjunction with the conducting coil shield 5 and the arcing horn 16, together with the 40 conducting coil shield 6. In this way, the arcs formed by the opening of the contact members of the switch are split up and quickly dissipated, with a minimum degree of deterioration to the apparatus, since the 45 coil shields 5 and 6 may be readily and inexpensively renewed whenever desired.

I do not wish to be restricted to the specific structural details or arrangement of parts herein set forth as various modifications thereof may be made without departing 50 from the spirit and scope of my invention. I desire, therefore, that only such limitations shall be imposed thereupon as are indicated in the appended claims.

55 I claim as my invention:

1. The combination with a plurality of relatively movable contact members, of plural means respectively located on opposite sides thereof and in proximity thereto for inductively quenching the arcs formed between said members, means for guiding said arcs around said quenching means, and means, secured to said contact members, for conducting portions of said arcs into close 60 proximity to the respective guiding means.

2. The combination with a plurality of relatively movable contact members, of plural means respectively located in proximity to the contact members for quenching the arcs formed therebetween, conducting means for guiding said arcs around both said quenching means, and means secured to said contact members for directing portions of said arcs toward the respective conducting means. 75

3. The combination with a plurality of relatively movable contact members, of plural means respectively located on opposite sides of said members for quenching the arcs formed between them, means interposed in the path of said arcs for effecting division thereof, and means for guiding the portions of the split arcs around the respective parts of said plural means. 80

4. The combination with a plurality of relatively movable contact members, of plural means respectively located on opposite sides of said members for quenching the arcs formed between them, a member of insulating material interposed in the path of said arcs for effecting division thereof, and conducting members for guiding the portions of the split arcs around the respective parts of said plural means. 90

5. The combination with a plurality of relatively movable contact members, of a plurality of magnetic blowout coils respectively located on opposite sides thereof and in proximity thereto for quenching the arcs formed between said members, means comprising conducting shields for said coils for jointly dissipating said arcs, and means secured to said contact members for directing portions of said arcs toward the respective conducting shields. 95

6. The combination with a plurality of relatively movable contact members, of a plurality of magnetic blowout coils located in proximity to the respective contact members for quenching the arcs formed therebetween, means comprising conducting shields for said coils for dissipating said arcs in opposite directions, and means secured to said contact members for directing portions of said arcs toward the respective conducting shields. 100

7. The combination with a plurality of relatively movable contact members, of a plurality of magnetic blowout coils located on opposite sides of said members for quenching the arcs formed between them, means disposed opposite the contact members in the path of said arcs for effecting division thereof, and means for guiding portions of the split arcs around said coil. 105

8. The combination with a plurality of relatively movable contact members, of a plurality of magnetic blowout coils for quenching the arcs formed between said members, means disposed opposite the con- 110

- tact members in the path of said arcs for effecting division thereof, and conducting means for guiding the portions of the split arcs around the respective coils.
5. 9. The combination with a plurality of relatively movable contact members, of a plurality of magnetic blowout coils alined with the contact members on opposite sides thereof to quench arcs formed therebetween,
10. a barrier of insulating material located opposite the contact members in the path of said arcs for effecting division thereof, and means comprising conducting shields for said coils for dissipating the portions of the
15. split arcs in opposite directions.
10. The combination with a plurality of relatively movable contact members, of a plurality of magnetic blowout coils located near the contact members on the respective
20. sides thereof to quench arcs formed therebetween, means comprising conducting mem-
- bers fully shielding said coils from said arcs and adapted to dissipate such arcs, and means secured to said contact member to direct portions of said arcs toward the respective conducting members.
11. The combination with a plurality of relatively movable contact members, of a plurality of magnetic blowout coils located near the contact members on the respective sides thereof to quench arcs formed therebetween, supporting members of insulating material for the respective sets of contact members and coils, and means comprising conducting shields secured to said supporting members and co-operating therewith to completely surround the respective coils.

In testimony whereof, I have hereunto subscribed my name this 19th day of Feb., 1919.

ARTHUR J. HALL.
